POCKETBOOK FRAME

Herbert J. Beilis, 35—45 81st St., Jackson Heights, N.Y.

Filed Nov. 12, 1958, Ser. No. 53,356

Term of patent 14 years

(Cl. D87—2)

FIG. 1

I claim:

The ornamental design for a pocketbook frame, as shown.
